Primary Examiner — Nathan M Johnston(74) *Attorney, Agent, or Firm* — Richard Bennett Salles(57) **CLAIM**

The ornamental design for a foldable table, as shown and described.

DESCRIPTION

U.S. Pat. No. D 564,250—Collapsible Table—Haimoff (2008)

U.S. Pat. No. D 754,991—Modular Wall Recessed Furniture Gosling (2016)

U.S. Pat. No. D 742,526S—Veterinary Table—Haake et al (2015)

U.S. Pat. No. D 618,939S—Convertible Wall Mount—Gibbs (2010)

U.S. Pat. No. 1,890,526—Folding Shelf—McEwing (1932)

U.S. Pat. No. 6,779,467 B1—Hideaway Desk—McCoy et al (2004)

U.S. Pat. No. 5,033,134—Cabinet Wall Bed—Burchett (1991)

FIG. 1 is a lower right perspective view of the foldable table showing my new design.

FIG. 2 is a rear view thereof.

FIG. 3 is a front view thereof.

FIG. 4 is a left side view thereof.

FIG. 5 is a right side view thereof.

FIG. 6 is a top plan view thereof; and,

FIG. 7 is a bottom plan view thereof.

1 Claim, 5 Drawing Sheets(56)
